ATTORNEY.

UNITED STATES PATENT OFFICE.

ALBERT R. NICOLAI, OF MONROE, MICHIGAN, ASSIGNOR OF ONE-HALF TO EDWARD J. KREUCHAUF, OF MONROE, MICHIGAN.

DOOR-HOLDING DEVICE.

Application filed April 21, 1926. Serial No. 108,434.

It is an object of this invention to provide a door holding device having a jaw which is adapted to be forced downwards into receiving position by a door striking it. Moreover the jaw is so mounted on a stationary portion of the device that as soon as the door has passed over it the jaw will rise of its own accord and hold the door between it and an upstanding flange integral with the stationary portion of the device.

Another object of the invention is to provide a door holding device having a jaw integral with a pivotal member having projections adapted to extend one on either side of the door when in held position, so that the jaw may be depressed and the door released from either side of the latter.

With these and other objects in view which will become apparent as the specification proceeds, the invention consists in certain novel construction and combination of parts hereinafter more fully described with the aid of the accompanying drawings.

Figure 1 illustrates a vertical section of the invention and portion of a door held between the jaw and the flange integral with the stationary portion of the device.

Figure 2 shows a vertical section of the invention with the jaw depressed and portion of a door passing over it.

Figure 3 is a plan view of the invention, and

Figure 4 shows a diagrammatic view of the holding device so placed as to hold garage doors open.

Referring to the drawings, 1 designates an angle-shaped plate the horizontal portion 2 of which is secured as to a block 3. The vertical flange 4 of the plate forms a stationary stop. The pivotal member 5 is provided with an opening 6 for the flange 4 to pass through, and a cotter pin 7 extends through the sides of the pivotal member 5 and through the plate 1 thereby constituting the fulcrum about which the member 5 turns. The jaw 8 integral with the pivotal member is so positioned with regard to the flange 4 that the intervening distance is slightly greater than the thickness of the door to be held. 9 indicates a downwardly inclined portion of the member 5 extending outwards from the top of the jaw 8. That portion of the pivotal member which is arranged over the horizontal portion 2 of the plate 1 is preferably provided with depending flanges

10 at its sides so as to minimize the possibility of dirt, snow and the like accumulating under the pivotal member and rendering it inoperative. The end 12 of the pivotal member projects beyond the plate 1 so as to afford a toehold for raising that end of the member and thereby lowering the jaw 8. 5^a indicates a stop, in this case integral with the underside of the member 5 and adapted to strike the top of the plate 1 to limit the swing of the member in one direction. It will also be noted that the pivotal member is so balanced that the jaw 8 is on the lighter end; because of this the device always returns to the position shown in Figure 1. 70

The outer end of the downwardly inclined portion 9 is lower than the bottom of the jaw 8 and should be so placed that as a door swings into the position in which it is to be held the lower edge of the latter, or a suitable notch cut therein, will contact the inclined surface of the portion 9 and depress the pivotal member until it has swung beyond the jaw 8, then the latter rises, due to the balance of the pivotal member, and the door is held between the jaw and the flange 4. 75

When it is desired to release the door either the inclined surface 9 is pressed down or the opposite end 12 of the member is raised according to which side of the door the person may be who wishes to move the door. Moreover it is apparent that either of these operations can easily be performed by anyone with their toe. 90

In the diagrammatic view in Figure 4 a garage 15 is illustrated, one door 16 of which is held open by a holding device 20, and the other door 17 is shown closed and a second holding device 21 so placed as to hold the door open when desired. The lower edges of the doors are provided with notches 22 which are engaged by the holding devices. 95

While a preferred embodiment of the invention has been described and shown, it is understood that the construction is susceptible to such changes as fall within the scope of the appended claims. 100

What I claim as my invention and desire to secure by Letters Patent is:

1. A door holding device comprising a stationary plate having a vertical flange adapted to form a stop, a member pivotally mounted on said plate and having an open- 110

ing therethrough for said vertical flange to pass through, and a jaw on said member so spaced from said vertical flange as to hold a door therebetween, said member being so mounted that it tends at all times to assume a substantially horizontal position.

2. A door holding device as described in claim 1 wherein that portion of the member which covers the plate is provided with downward flanges extending below said plate.

3. A door holding device comprising a stationary plate having a flange at right

angles to its length adapted to form a stop, a member pivotally mounted on said plate having an opening therethrough for said flange to pass through a jaw, on said member the holding surface of which is opposed to said flange, the end of said member in proximity to said jaw having a downwardly and outwardly tapered surface terminating at its outer end below the jaw holding surface, the opposite end of said member extending beyond the end of said plate, and a stop to limit the turning movement of said member.

ALBERT R. NICOLAI.
